PROCESS FOR REMOVING METALLIC CONTAMINANTS FROM RESIDUAL OILS

Robert L. Menk, Iselin, N. J., assignor to Esso Research and Engineering Company, a corporation of Delaware

Application December 14, 1954, Serial No. 475,135

10 Claims. (Cl. 196—14.46)

This invention relates to a method of removing metallic contaminants from residual oils, and more particularly to a method for removing such contaminants by contacting the residual petroleum fraction with a wash solvent which removes the metallic contaminants without increasing the aromatic content of the residual oil.

In the past it has been proposed to treat residual petroleum fractions in various ways to remove certain metallic contaminants therefrom. Practically all residual petroleum fractions contain substantial amounts of nickel, vanadium, and iron in various forms. Such oils have been found to be undesirable feed stock for catalytic cracking operations due to the presence of these metallic contaminants which are responsible for catalyst poisoning or contamination. Generally, it is desired to reduce the metallic content of the cracking feed stock to below one part per million. One method that has been proposed has been the use of a so-called "wash oil" which contains substantially no metallic components. The principle behind this operation is that a high driving force exists to transfer the metallic compounds from the residual oil to the wash oil. This transfer operation may be carried out in conjunction with a deasphalting step. Asphalt precipitated from the wash oil descends through a deasphalting tower countercurrent to an ascending deasphalting metal containing oil. The descending asphalt lean in metals content scrubs the metallic components from the oil. Heavy fractions derived from catalytic cracking and lean in metallic contaminants are prime sources of wash oil for this purpose. However, these oils are characteristically high in content of aromatic compounds. Hence, any wash oil that is not precipitated in the deasphalting tower is removed in the deasphalting oil phase and contributes to an undesirable buildup of aromatic compounds therein. In other words, removal of metallic contaminants is improved at the expense of increasing the aromaticity of the deasphalting residual oil.

It is an object of the present invention, therefore, to provide a method for removing metallic contaminants from residual petroleum fractions while substantially preventing undesirable increases in aromatics content in the treated oil.

It is a further object of the present invention to provide a process wherein residual petroleum fractions containing metallic contaminants are deasphalting and the deasphalting phase washed with a material capable of removing metallic constituents therefrom but incapable of transferring aromatic constituents thereto.

These and additional objects, which will be in part apparent and in part specifically pointed out in the ensuing description, are attained by treating a catalytically cracked petroleum hydrocarbon material containing a substantial amount of aromatic compounds and boiling above about 600° F. in a first deasphalting zone with a liquefied normally gaseous hydrocarbon to produce a first asphalt phase and a first deasphalting phase. The first asphalt phase is then introduced into a second deasphalting zone. A petroleum feed stock containing a substan-

2

tial amount of metallic contaminants is introduced into the second deasphalting zone in conjunction with additional liquefied normally gaseous hydrocarbons and there contacts the first asphalt phase. This produces a second deasphalting phase, lean in metal contaminants, and a second asphalt phase containing the metallic contaminants. The second deasphalting phase is removed and used as a feed stock for a catalytic cracking operation while the second asphalt phase is fluxed with the deasphalting phase from the first deasphalting operation. By controlling the temperatures in the deasphalting zones so that the lowest temperature in the second zone is higher than the lowest temperature in the first zone, the asphalt phase produced in the first zone is of sufficiently high molecular weight to preclude the transfer of aromatics to the deasphalting oil fraction in the second deasphalting zone. In other words, by maintaining a differential between the minimum temperatures in the deasphalting zones, separation of additional aromatics from the wash oil in the second zone is prevented.

The present invention may be better understood by reference to the accompanying single figure of drawings, which is a diagrammatic representation of a typical process embodying the invention.

Turning now specifically to the drawings, a heavy cracked material such as cycle oil from a catalytic cracker or tar resulting from the thermal cracking of cycle oil and a liquefied normally gaseous hydrocarbon such as liquid propane are combined in the mixing zone 15 and transferred to the first deasphalting stage 11. In the first deasphalting stage 11 the temperature of the ingredients is controlled to effect the precipitation of asphaltic material of relatively high molecular weight. Normally the temperature in this stage is maintained between about 100° F. and 200° F., preferably between about 100° F. and 120° F. The heavy asphalt phase is removed from the first deasphalting zone through line 12, together with dissolved hydrocarbon solvent, while the lighter deasphalting phase is removed through line 13. The heavy asphalt phase or wash oil is transferred through line 12 to a point near the top of the second deasphalting zone 14. The second deasphalting zone is preferably in the form of a vertically disposed tower through which the heavy asphalt phase drops countercurrent to the rising stream of lighter deasphalting residual feed stock. The residual feed stock, containing more than one part per million of metallic contaminants, is introduced through line 15 near the middle of the second deasphalting zone at a point above that at which additional liquefied hydrocarbon solvent is introduced through line 16. Normally temperature conditions in the second deasphalting zone 14 are so controlled as to provide a temperature gradient between the top 17 and the bottom 18, with the temperature at the top of the tower being higher. The temperature at the bottom of the second deasphalting tower, that is, the temperature at which the hydrocarbon solvent is introduced, must be maintained at least as high as the temperature of the first deasphalting zone in order to prevent the transfer of additional aromatic materials from the wash oil to the feed stock being deasphalting. In the second deasphalting zone 14 the residual feed stock introduced at 15 flows downwardly against the rising stream of light hydrocarbon and is deasphalting. The deasphalting oil rises toward the top 17, and between the point of introduction 15 and the top 17 passes countercurrent to the downwardly flowing wash oil. This wash oil is essentially free of metallic contaminants so that it serves to strip these undesirable materials from the deasphalting oil while contacting it. The deasphalting oil is then removed from the top of second deasphalting zone 14 through line 19 and may then be passed, after solvent removal, to a catalytic cracking

operation, which may be carried out more successfully and with reduced danger of catalyst contamination due to the fact that metallic contaminants have been removed from the residual feed stock. The wash oil and asphalt precipitated in the lower section of the second deasphalting zone are removed together through line 20 at the bottom of the deasphalting zone. This heavy material is then fluxed with the deasphalting phase from the first deasphalting zone in order to facilitate handling and the resulting mixture passed to a solvent recovery unit, which may be of any conventional design.

As previously stated, the temperature conditions in the second deasphalting zone must be maintained such that the minimum temperature in the second deasphalting zone is higher than the minimum temperature in the first deasphalting zone 11. The differential between these minimum temperatures may be as little as 5° F., but larger differentials in the order of 30°-70° F. are preferred. In order to prevent undesired transfer of aromatics to the deasphalting oil, it is essential that a differential between these minimum temperatures be maintained. Typically the temperature in zone 14 will be maintained in the range of about 105°-250° F., and preferably in the range of about 150°-230° F. In the second deasphalting zone it is preferred to employ a liquefied normally gaseous hydrocarbon, preferably C₃ or C₄ or mixtures of these hydrocarbons, in the amount of from about 2 to 10 volumes of hydrocarbon per volume of petroleum feed stock, with a preferred range being from about 3 to about 6 volumes. In the first deasphalting zone it is preferred to use the same hydrocarbon solvent. The aromatic cracked fraction to be deasphalting is introduced in the amount of 5% to 30% based on the volume of feed stock deasphalting in the second tower, with a range of from about 10% to about 20% being preferred. The amount of wash oil employed in the second deasphalting zone will amount to from about 2% to about 15% based on the volume of feed stock.

The feed material for the first deasphalting zone, i. e., the material from which the wash oil is prepared, may consist of any one or more of a number of materials. A preferred material for this purpose is so-called "cycle oil," which is a residual highly aromatic fraction obtained from a catalytic cracking operation and having an initial boiling point above about 600° F. and preferably above about 750° F. Heavy thermal tar obtained as a residue from the thermal cracking of cycle oil is also a suitable source of asphalt for wash oil. Since a principal object of the present invention is the minimizing of transfer of aromatics from wash oil to cracking stock, it applies to sources of wash oil high in aromatics content. Such materials are usually products of catalytic cracking operations and normally contain upwards of 50% by weight of aromatic compounds.

The following examples illustrate the operation of the process of the present invention and demonstrate the advantages to be obtained through its use, namely, the removal of metallic contaminants from a feed stock while at the same time minimizing an increase in aromaticity.

EXAMPLE I

In this example a comparison is made between the results obtained by using a catalytic tar as a wash oil in a deasphalting operation and the results obtained in a deasphalting operation employing no wash oil. In the results set forth in Table I below, a liquefied mixture of propane and butane (70-30) was employed as the deasphalting solvent. In each case a solvent to feed oil volume ratio of 3.5 to 1 was used and a temperature gradient of from 151° F. at the bottom of the tower to 171° F. at the top of the tower was maintained. The results obtained for using 10% volume catalytic tar (based on the volume of feed stock) as wash oil and using no wash oil are given below.

4
Table I

	Deasphalting Oil Without Wash Oil	Deasphalting Oil With Wash Oil	Feed Stock	Catalytic Tar
5				
Yield in Volume percent on feed	48.4	53.5		
Specific Gravity	0.9451	0.9848	1.012	1.115
Conradson Carbon, Weight percent	4.4	4.1	19.7	19.1
Nickel content, parts per million	2.0	0.6	21.7	<0.42
Aromatic Index (percent by weight of aromatic rings)	15.1	29.7		

15 In operating the deasphalting using the catalytic tar as wash oil, the tar was injected into the top section of the deasphalting tower. The precipitated asphalt from this tower flowed downward countercurrent to the deasphalting oil phase, and, as seen from the results set forth above, served to drastically reduce the nickel content of the oil. However, it is to be noted that this improvement is gained at the expense of a severe buildup in the aromaticity of the deasphalting oil, as indicated by an increase of from 15.1% to 29.7% by weight of aromatic rings, and also by the high specific gravity of the deasphalting oil.

EXAMPLE II

30 A heavy catalytic tar of the same type employed as a wash solvent in Example I was deasphalting using a mixture of liquid C₃-C₄ hydrocarbons (30% C₄) in a deasphalting tower having a top temperature of 170° F. and a bottom temperature of 151° F., to produce a light deasphalting oil and a reduced catalytic tar fraction. A ratio of hydrocarbon solvent to oil of 3.3 to 1 was employed in this deasphalting operation. Table II below gives the inspections of the catalytic tar, the deasphalting oil, and the asphalt formed. The asphalt was subsequently used as a wash solvent using the same residual petroleum fraction deasphalting according to Example I.

Table II

	Cycle Stock From Catalytic Cracking	Deasphalting Oil	Asphalt
45			
Yield, Volume Percent on Feed		39.8	60.2
Specific Gravity at 60° F.	1.115	1.027	1.173
Conradson Carbon, Weight Percent		4.4	42.0
50 Viscosity, S. S. U.	19.1 11.2	9.0 (275° F.)	105 (300° F.)
Modified Naphtha Insolubles, Weight Percent	12.6	0.1	30.1
Nickel Content, parts per million	<0.42	0.2	0.49

55 The second deasphalting operation was carried out using liquefied butane solvent in a ratio of six volumes of solvent per volume of feed oil. For comparison, two runs are given, one in which deasphalting was carried out using no wash solvent and another which employed 10% by volume of the asphalt precipitated according to the conditions just set forth. Table III below gives the inspections of the deasphalting oil obtained with and without wash solvent.

Table III

	Employing 10% By Volume of Feed of Asphalt as Wash Oil	Deasphalting Using No Wash Oil
70		
Yield, Percent By Volume on Feed	62.5	63.0
Specific Gravity (60° F.)	0.9613	0.9606
Conradson Carbon, Weight Percent	6.2	7.2
Nickel Content, parts per million	1.3	3.7
Aromatic Index (Weight Percent of Aromatic Rings)	22.0	21.0

In carrying out the run using wash solvent, the deasphalting temperature at the top of the tower was 221° F. and at the bottom 199° F. with the hydrocarbon solvent introduced in the middle at 203° F. In the run employing no wash oil the temperature conditions were 226° F. at the top of the tower, 201° F. at the bottom, with the residuum introduced in the middle at 201° F. The wash oil was injected near the top of the tower. Thus it will be seen that the deasphalting conditions in both runs were substantially the same with the presence or absence of asphalt as wash oil being the only difference in the runs. Comparison of the data from the two runs clearly illustrates the advantages of the process of the present invention. Not only is the nickel content substantially less, but the aromatics content of the deasphalting oil is not substantially increased as it would have been had the second deasphalting step been carried out under such conditions as to permit asphalt precipitation from the wash oil. The undesirable effects of this have been illustrated in Table I.

It is to be understood, of course, that either the first or the second deasphalting step may be carried out under conditions of constant temperature rather than in towers having a temperature gradient from top to bottom. It is necessary, however, that the minimum temperature in the second deasphalting stage always be higher than the temperature in the first deasphalting stage. Maintenance of such a temperature differential is necessary to avoid the solution of asphalt or aromatic material from wash oil in the second deasphalting stage with the concomitant transfer of aromatic materials to the deasphalting feed stock. In practice, however, it is generally advisable to carry out both deasphalting steps using a temperature gradient across each individual deasphalting zone.

Although there have been described in connection with the present invention specific embodiments thereof using particular materials and temperatures, it will be understood that various other equivalent materials and operating conditions may be employed without departing from the invention as defined by the following claims.

What is claimed is:

1. A method for treating a petroleum fraction feed stock containing a major portion of components boiling above 900° F. and contaminated by a substantial amount of metallic contaminants comprising the steps of treating a catalytically cracked hydrocarbon fraction containing a substantial amount of aromatic hydrocarbons in a first deasphalting zone with a liquefied normally gaseous hydrocarbon, maintaining deasphalting conditions in said zone to produce a first asphalt phase and a first deasphalting phase, withdrawing said first asphalt phase from said first deasphalting zone, introducing said first asphalt phase into a second deasphalting zone maintained at deasphalting conditions, introducing said feed stock and liquefied normally gaseous hydrocarbon into said second deasphalting zone to produce a second deasphalting phase containing less metal contaminants than said feed stock and a second asphalt phase containing metal contaminants from said feed stock, regulating the temperatures in said deasphalting zones so that the minimum temperature in said second zone is always higher than the minimum temperature in said first zone, and withdrawing said second deasphalting and second asphalt phases from said second deasphalting zone.

2. The method according to claim 1 wherein a temperature differential of at least about 5° F. is maintained between said minimum temperatures of said deasphalting zones.

3. The method according to claim 1 wherein a tem-

perature differential of from about 30°-70° F. is maintained between said minimum temperatures of said deasphalting zones.

4. The method according to claim 1 wherein said second asphalt phase is combined with said first deasphalting phase after said second asphalt phase is withdrawn from said second deasphalting zone.
5. The method according to claim 1 wherein said deasphalting temperatures are maintained in the range of from about 100° F. to about 250° F.
- 10 6. The method according to claim 1 wherein said first asphalt phase introduced into said second deasphalting zone amounts to about 2% to about 15% by volume in proportion to said feed stock.
- 15 7. The method according to claim 1 wherein said cracked hydrocarbon fraction has an initial boiling point of above about 600° F.
8. The method according to claim 7 wherein said cracked hydrocarbon fraction is cycle oil.
- 20 9. A method for treating a residual petroleum fraction boiling above about 900° F. and containing more than about 1 part per million of metallic contaminants selected from the group consisting of iron, vanadium, and nickel to reduce the metallic content thereof while not
- 25 substantially increasing the aromatic content thereof, comprising the steps of introducing a catalytically cracked hydrocarbon fraction containing a substantial amount of aromatic hydrocarbons into a first deasphalting zone, said deasphalting zone having a high temperature end
- 30 maintained at about 170° F. and a low temperature end maintained at about 150° F., contacting said cracked hydrocarbon fraction in said first deasphalting zone with a liquefied, normally gaseous hydrocarbon to produce a first asphalt phase and a first deasphalting phase, with-
- 35 drawing said first asphalt phase from the high temperature end of said first deasphalting zone, introducing said first asphalt phase into the high temperature end of a second deasphalting zone, said second deasphalting zone having a high temperature end maintained at about 220°
- 40 F. and a low temperature end maintained at about 200° F., introducing said residual petroleum fraction into said second deasphalting zone at a point intermediate said ends, introducing liquefied, normally gaseous hydrocarbon into said second deasphalting zone intermediate
- 45 said ends, deasphalting said residual petroleum fraction in said second deasphalting zone to produce a second deasphalting phase containing less metallic contaminants than said feed stock and having substantially the same aromatic content as said residual petroleum fraction, and
- 50 a second asphalt phase containing metallic contaminants from said feed stock, withdrawing said second asphalt phase from the low temperature end of said second deasphalting zone and withdrawing said second deasphalting phase from the high temperature end thereof, and sub-
- 55 sequently fluxing said second asphalt phase with said first deasphalting phase.
10. The method according to claim 9 wherein the amount of cracked hydrocarbon introduced into said first deasphalting zone amounts to from about 5% to about
- 60 30% by volume of the residual petroleum fraction introduced into said second deasphalting zone.
